UNITED STATES PATENT OFFICE.

JOSHUA P. SESSEMAN, OF FOREST GROVE, OREGON.

MUSIC-RACK.

No. 895,049.

Specification of Letters Patent.

Patented Aug. 4, 1908.

Application filed December 24, 1907. Serial No. 407,964.

To all whom it may concern:

Be it known that I, JOSHUA P. SESSEMAN, a citizen of the United States, residing at Forest Grove, in the county of Washington 5 and State of Oregon, have invented certain new and useful Improvements in Music-Racks; and I do declare the following to be a full, clear, and exact description of the invention, such as will enable others skilled 10 in the art to which it appertains to make and use the same.

This invention relates to music racks, and more particularly to music leaf turners used in connection therewith.

15 The object of the invention is to provide a device which will enable the musician to turn the leaves of the music upon the rack while using both hands in playing, for instance, a violinist is completely handicapped 20 by having to turn the pages of his music. Other musicians also have the same difficulty, and it is the object of my invention to provide a device which will enable them to turn the sheets with an operation of the foot.

25 A further object is to provide a device of this character which may be folded up with the rack in compact form for purposes of transportation.

30 A still further object is to cheapen the construction of such devices heretofore in use so as to be within reach of all, and at the same time to produce a leaf turner which will be substantial, efficient in operation, and with neat in appearance.

35 Other objects will appear as the following specific description is read in connection with the accompanying drawings, in which,

Figure 1 is a front elevation of the device; Fig. 2 is an enlarged fragmentary perspective view of the upper end of the standard with the rack removed, Fig. 3 is an enlarged longitudinal section of the standard; Fig. 4 a vertical section of the device; and Fig. 5 is a sectional view of the standard and operating rods, taken on line $x-x$ of Fig. 1.

Referring more especially to the drawings, 1 represents a tubular standard of any suitable material, and of sufficient length and diameter to receive the operating rods 2 and 50 3. These rods are somewhat cylindrical in cross section, and are secured together so as to be longitudinally reciprocable one upon the other, and with their flat sides together, by the securing bands 4 passed around both 55 rods, and secured to one of them.

At the upper end of the standard is se-

cured an apertured casting 5, having a rearwardly projecting lug 6 to which is secured a supporting arm 7, by the bolt 8, which passes through apertures in the lug 6 and in the 60 supporting arm 7. An adjusting nut 9 is carried upon the bolt so that the supporting arm may be tilted backwards and forwards as is desired. This supporting arm is provided at its upper end with a squared portion 65 10, which engages a lug 11 having a square aperture therein, and also is surrounded by a band 12. Both the apertured lug 11 and the band 12 are carried upon the back of the center-piece 14 of the usual music rack 13. 70 It will be seen that by adjusting the arm 7, I am enabled to tilt the music rack to any position desired.

Journalized upon the front of the center piece 14 in bearings 15 is a vertical rod 16, 75 notched upon its front face, as at 17, to receive the pawl 18 of a horizontally extending arm 19, provided adjacent its outer end with a clamping device 20, which is adapted to connect the arm with the music 21. At the 80 bottom of the rod 16 I provide a flexible connection or shaft 22, which is provided at its lower end with a collar 23, having a central squared opening therein to receive the squared end 24 of the upper rod 2. This upper rod is provided with collars 25, which engage opposite sides of a collar 26, secured to the upper standard 1, so as to prevent vertical movement thereof.

85 Adjustably connected to the bottom of the standard is a supporting arm 27, which is provided with a laterally extending foot 28, in which is stepped the lower end of the operating rod 3. This arm 27 is connected to the adjusting band 29 in any suitable manner, so that it may be raised or lowered, and carry with it the operating rod 3. Pivoted to the foot 28 is a segmental rack 30, having projecting therefrom a foot lever 31. The rack is normally held in engagement with the pinion 32 secured to the lower end of the rod 3 in any suitable manner, so that by the operation of the foot lever the rod 3 may be turned, and through it the rod 2 and the arm 19.

100 Suitable supporting legs are connected to the standard by an adjustable band 34, and are held in operative position by truss members 35, adjustably connected to the standard by the band 36.

105 It will be seen that as shown in Fig. 1, the arm 19 rests against the supporting members on the right hand side of the arm 13. To

turn the sheet of music 21, the clamp 20 is secured thereto, and at the proper time the foot lever 31 is depressed to move the rack 30 from the pinion 32, and thereby turn the 5 rods 3 and 2, and through the flexible shaft 22, the rod 16 and the arm 19.

When it is desired to return the piece of music to its normal position, the toe is slipped 10 under the lever 31, and the parts are returned to normal by giving the foot an upward movement.

To fold the device for transportation, the pawl 18 or the arm 19 is disengaged from the rack, and the arm is slipped down over the 15 rod 16 to the lower bearing 15, and is then folded along the bar 16. The frame is then folded in the usual manner and removed from its connection with the rod 2, and the arm 7. The lever 31 with its accompanying 20 parts, comprising the supporting rod 27 and the band clamp 29, is slipped up on the standard, and the foot lever 31 is folded up so as to be parallel with the standard 1. The supporting legs 33 and their truss members 35 25 are folded in the usual manner, and need no further description.

Many other modifications might be resorted to in practice, and all such modifications are considered by me as within the purview of the appended claims.

Having described my invention, what I claim as new and desire to secure by Letters-Patent is:

The combination with a music stand, of a 30 foot-operated lever depending therefrom, means to adjust the lever with respect to the stand, an operating rod and connections whereby it is adapted to be rotated by said foot lever, another rod upon which the first mentioned rod is reciprocally mounted, a 35 music rack, a leaf turner mounted thereon, a flexible connection between the last mentioned rod and the leaf turner, and means to adjust the rack laterally with respect to the last mentioned rod.

In testimony whereof I have hereunto set my hand in presence of two subscribing witnesses.

JOSHUA P. SESSEMAN.
